UNITED STATES PATENT OFFICE.

GEORGE Q. ADAMS, OF QUINCY, ILLINOIS.

DESIGN FOR A FENCE-PICKET.

SPECIFICATION forming part of Design No. 15,982, dated March 24, 1885.

Application filed July 24, 1884. Term of patent 3½ years.

To all whom it may concern:

Be it known that I, GEORGE Q. ADAMS, a citizen of the United States, residing at Quincy, county of Adams, State of Illinois, have invented and produced a new and useful and original Design for Fence-Pickets, of which the following is a specification, reference being had to the accompanying drawings, forming a part of this specification.

10 Figure 1 is a front elevation of my new design for picket. Fig. 2 is a sectional view through line xx , Fig. 1.

15 The leading features of my design for a picket are the surface ornamentation of the same, representing a "cyma reversa," bounded on the sides by curved edges, a semi-spherical top, and right-angular bottom; and my design consists in a picket having this shape or configuration.

A is the picket, the surface of which is 20 shaped as shown in Fig. 2, the same consisting of the curve b and curves $c c$, with curved edges $e e$. The picket thus presents the appearance of a cyma-reversa surface.

Having thus described my invention, I desire to claim—

The design for a fence-picket having a cyma-reversa surface and bounded upon the sides by curved edges, and provided with a semi-spherical top and right-angular bottom, as described and shown.

Signed at New York, in the county of New York and State of New York, this 23d day of July, A. D. 1884.

GEORGE Q. ADAMS.
